DESIGN FOR A DISK HARROW

John F. Rude, Evansville, Ind., assignor to Blount
Plow Works, Evansville, Ind., a corporation of
Indiana

Application January 5, 1942, Serial No. 105,021

Term of patent 14 years

To all whom it may concern:

Be it known that I, John F. Rude, a citizen of the United States residing at Evansville, in the county of Vanderburgh and State of Indiana, have invented a new, original, and ornamental Design for a Disk Harrow, of which the following is a specification, reference being had to the accompanying drawings, forming a part thereof wherein:

Fig. 1 is a perspective view of a disk harrow showing my new design;

Fig. 2 is a rear elevational view thereof;

Fig. 3 is a plan view thereof; and

Fig. 4 is a side elevational view thereof.

I claim:

The ornamental design for a disk harrow substantially as shown.

JOHN F. RUDE.
